COMBINATION LIPSTICK CONTAINER AND MIRROR

George Abe Laughton, Lowsonford, England

Application April 26, 1954, Serial No. 30,195

Term of patent 14 years

(Cl. D86—10)

FIG.1.

FIG.2.

FIG.3.

FIG.4.

FIG.5.

I claim:

The ornamental design for a combination lipstick container and mirror, as shown.
